UNITED STATES PATENT OFFICE.

THOMAS O. MILLER, OF HOUSTON, TEXAS.

CAR-BRAKE.

SPECIFICATION forming part of Letters Patent No. 618,230, dated January 24, 1899.

Application filed February 23, 1897. Serial No. 624,635. (No model.)

To all whom it may concern:

Be it known that I, THOMAS O. MILLER, a citizen of the United States, residing at Houston, in the county of Harris and State of

5 Texas, have invented certain new and useful Improvements in Car-Brakes; and I do hereby declare the following to be a full, clear, and exact description of the invention, such as will enable others skilled in the art to which it app-

10 pertains to make and use the same.

My invention relates to brakes for cars or other vehicles, and has for its object to so construct the same that its operation will be quick, effectual, and great leverage power be- 15 furnished.

With these and other objects in view my invention consists in the construction, arrangement, and combination of parts and in the various details thereof, as will be first 20 fully pointed out in the specification and then claimed.

In the drawings forming a part of this specification, and in which like symbols of reference represent corresponding parts in the several 25 views, Figure 1 is a vertical sectional view of my improved brake. Fig. 2 is a similar view, partly in section. Fig. 3 is a plan view of the ratchet-wheel case, partly broken away, showing a different form of spring for actu- 30 ating the pins or pawls. Fig. 4 is a sectional plan view on line 4 4 of Fig. 1. Fig. 5 is a similar view to Fig. 4 on line 5 5 of Fig. 1. Fig. 6 shows pawl and ratchet-wheel for holding the brake when being operated. Fig. 7 35 is a plan view of a modification of spindle upon which are journaled bevel-gears for communicating motion from one of the gears to another. Fig. 8 is a view of one of the bevel-gears; and Fig. 9 is a modification of 40 the device, the ratchet-wheel case being partly broken away to show the interior thereof, the locking spring-pins being located at top and bottom of the gears instead of at the sides.

45 A represents the floor of the platform of the car; B, the dash-rail of the same; C, the ratchet-wheel case, and D the lever for operating the same.

E is the rod or shaft that runs from the 50 ratchet to the clutch; E', the spool upon which the brake-chain is wound.

b is the top bevel and ratchet wheel, keyed

to the rod E; b', the bottom bevel and ratchet wheel, loose on sleeve F, and c gears for communicating motion from the upper to the 55 lower gears b b'.

d is the shaft on which bevels c are journaled, said shaft being screwed onto sleeve F and having nuts d' for holding said bevels on the same.

60 f f' are spring pins or pawls for upper and lower gears, having springs f² for actuating the same, said pawls locking the ratchet or bevel wheels when the lever is operated, the upper ratchet running from left to right and 65 the lower from right to left, as will be apparent from the drawings. Thus it will be seen that when the lever D is operated the casing C will be rotated, carrying the gear b and shaft E to the right, winding the chain 70 upon the spool E'. The gear b' in the meantime is locked against forward motion with relation to the casing by pawl f but said pawl when the casing is rotated rides freely over the teeth of gear b'. The sleeve F being normally locked against rearward motion by the pawl h, it will be apparent that when 75 the crank-handle is operated only a forward motion is possible, and when it is desired to release the brake the pawl h may be thrown 80 out of engagement with the ratchet J or the foot-pin be depressed, allowing the spool to unwind.

G is the bottom of the ratchet-casing, which is secured upon sleeve F by being screwed 85 upon the same and is provided with internal screw-threads g', which engage with external threads upon the sleeve, and being provided with set screw or screws g².

H is a plate that fits around sleeve F and 90 fastens the same to the dash.

J is a ratchet-wheel keyed to sleeve F and engaged by dog h, pivoted on the platform of the car.

K is a sleeve or bearing connected to the 95 platform by means of screws or bolts j, the shaft E being journaled in the same.

K' K² represent the upper and lower portions of the clutch by means of which the device is locked and unlocked at pleasure by 100 foot-pin k, the clutch K² being held normally locked by means of spring k'.

m is a pin connecting the lower portion of the clutch K² with spool E', said spool por-

tion of the shaft being separate from the upper portion.

5 M M' are brackets which brace and hold the device in place, said brackets being attached by suitable bolts m' m² to the under side of the platform.

10 P is a bracket in which lever k² is journaled, said bracket being secured by suitable bolts on the under side of the platform. The outer end of the lever k² is preferably forked, so as to embrace the collar or clutch K', being held in place on the same by means of flange p on the clutch.

15 R is a screw-bolt entering the spool E' and adapted to attach the brake-chain S thereto. The lower end of shaft E is made square, as also the upper portion of the clutch K', so as to prevent it rotating on the shaft, but permitting a limited vertical movement of the 20 same. On the upper end of the shaft E is an annular groove to correspond with an internal groove on the top of the ratchet-wheel case, said grooves being for the purpose of receiving bearing-balls t.

25 In Fig. 3 is shown a different form of spring for actuating the spring-pins; but I prefer the form shown in Fig. 1, as the tension of the springs may be regulated.

The operation of my device is as follows: 30 By turning the lever D the ratchet-casing is rotated, communicating motion to the gears within, which in turn operate the shaft and the brake-chain is wound thereon. As already stated, the gear b is keyed to shaft E, and 35 the pawls f locking the same against backward motion the rotation of the casing C will operate said gear, which communicates motion to gears c, which in turn operate gear b', said gear b' being locked against forward motion. When it is desired to release the same, 40 the foot-pin is depressed and the mechanism is immediately set free; or, if desired, the dog h may be released (which is normally locked) from the ratchet-wheel J by the foot of the

motorman, so that the sleeve F will be freed, 45 and only partially or wholly release the brake, as desired.

In Fig. 9 is shown a modification of the ratchet arrangement, the same having ratchets at top and bottom instead of at the sides, 50 the operation being the same as that hitherto referred to in my preferred form.

Having now fully described my invention, what I claim as new, and desire to secure by Letters Patent, is—

55 1. In a brake, the combination with the lever, of a shaft adapted to be rotated by said lever, a sleeve surrounding the shaft, a ratchet-wheel keyed to the sleeve and adapted to be locked or unlocked by means of a pawl, a series of gears, a casing inclosing said gears and having interlocking mechanism connected therewith, so that the brake-chain may be wound and automatically locked, a clutch on the shaft, and a foot-pin and lever for throwing 60 said clutch out of operative position.

2. In a brake, the combination with the lever, of a shaft adapted to be rotated by said lever, a sleeve surrounding the shaft, a ratchet-wheel keyed to the sleeve and adapted to be 65 locked or unlocked by means of a pawl, a series of gears, a casing inclosing said gears and having interlocking mechanism connected therewith, so that the brake-chain may be wound and automatically locked, a clutch on the shaft, a foot-pin and lever for throwing 70 said clutch out of operative position, a spring to normally hold the clutch locked, a spool 75 connected with the lower portion of the clutch, and brackets supporting said clutch and spool 80 below the platform of the car.

In testimony whereof I affix my signature in presence of two witnesses.

THOMAS O. MILLER.
